UNITED STATES PATENT OFFICE.

EMIL OTTO KNISCHEWSKY, OF HAMILTON, ONTARIO, CANADA.

GOAL-KEEPER'S GUARD.

Application filed December 7, 1925. Serial No. 73,788.

My invention relates to improvements in goal keeper's guards and the object of the invention is to provide a more efficient guard than those hitherto used.

5 My invention consists essentially in a pair of guards so formed that when secured upon the wearer's legs, each leg occupies a position with respect to its guard offset laterally inward from the centre line of the guard so 10 that the portion of the guard projecting laterally outward from the leg is greater than the portion projecting laterally inward, all as hereinafter more particularly described and illustrated in the accompanying drawings in which:—

Fig. 1 is a front view of the guard for the right leg constructed in accordance with my invention.

Fig. 2 is a transverse section on the line 20 2—2 of Fig. 1.

In the drawings, like characters of reference indicate corresponding parts in the different views.

25 My improved guard comprises a heavily padded body portion 1 which is ribbed after the usual manner on its front face with upper and lower longitudinal ribs 2 and 3 and with transverse ribs 4 at the knee.

The body portion 1 is mounted upon a rear felt piece 5 and at the sides of the front face are auxiliary pads 6 and 7.

30 Formed in the rear face of the guard is a longitudinal leg receiving depression 8 which depression is offset laterally inward from the centre line of the guard.

In the guard for the right leg, as illustrated, this depression is offset towards the left while in the guard for the left leg it would be offset towards the right.

Straps for attaching the guard in position upon the leg are indicated by the numeral 9.

In using my guard it is placed against the leg so that the leg lies within the depression 8 and is secured in position by a number of 45 straps 9.

The toe of the foot projects through the cut away portion 10 at the bottom of the guard.

The position occupied by the leg is indicated in broken lines at 11 in Fig. 2.

From the foregoing description taken in conjunction with the drawings, it will be seen that when the guard is secured in position the guard extends laterally outward at 55 "A" to a greater extent than it extends laterally inward at "B".

Only one guard, that for the right leg, is illustrated but the guard for the left leg is exactly similar except that the leg depression 8 is offset towards the other side of the centre line.

From the foregoing it will be apparent that I have devised a novel form of goal keeper's guard whereby the objects of my 65 invention have been attained.

What I claim as my invention is:

A goal keeper's guard comprising a comparatively thick padded body portion having a vertically disposed leg receiving recess sunk into the rear face thereof, said recess offset laterally towards one vertical edge of the guard so that the guard extends laterally to a greater extent on one side of the recess than on the other side.

EMIL OTTO KNISCHEWSKY.
